LUBRICATOR PAD

Robert E. Murray, 711 Southampton Ave.,
Norfolk, Va. 23510
Filed June 1, 1965, Ser. No. 459,999
2 Claims. (Cl. 308—243)

This invention relates to lubricating means for the journal boxes of railway cars, and particularly to lubricator pads of the general nature of the one disclosed in my prior Patent No. 2,992,051, issued July 11, 1961.

The superiority of lubricator pads over other means for journal lubrication is well recognized. They are easier to handle, provide good lubrication, and do not harm the journal boxes as waste and other materials do. There are some excellent lubricator pads on the market, but there are times when problems are still encountered.

The general object of the present invention is to provide an improved lubricator pad which will eliminate many of the remaining problems of complete and trouble-free journal lubrication.

A more specific object of the invention is the provision of a pad which will clear itself quickly of any trash which may get on the journal-engaging surface of the pad.

Another object is to provide such a lubricator pad which will adapt itself to journal boxes having different depth lubricant sumps.

A further object is to provide a pad which has direct wicking paths from top to bottom without interruption by seams, or other obstructions.

Other objects of the invention will appear from the following description of one practical embodiment thereof, when taken in conjunction with the drawings which accompany, and form part of, this specification.

In the drawings:

FIGURE 1 is a perspective view of a lubricator pad embodying the principles of the present invention;

FIGURE 2 is a vertical section taken through a journal box with a lubricator pad in place, the pad being broken away to show interior structure;

FIGURE 3 is a transverse section through a portion of the journal box and the lubricator pad, taken on the line 3—3 of FIGURE 2 and shown on an enlarged scale; and

FIGURE 4 is a partial horizontal section through the end portion of the pad, and is taken on the line 4—4 of FIGURE 1.

In general, the lubricator pad of the present invention is of the type having a core of resilient synthetic rubber or plastic material and an outer case of wicking material.

Referring to the drawings in detail, and first to FIGURE 2, there is shown a conventional journal box 1 of the type used on railway cars. The box includes the usual housing 2, having a sump in the bottom forming an oil reservoir 3. There is a dust guard seat 4 and dust guard 5 at the inside, and the journal 6 with its button 7 projects into the box. Bearing 8, held in place by wedge 9, rests upon the journal in conventional manner.

The lubricator pad 10 is adapted to fit within the box, between the bottom of the oil reservoir and the journal. The pad consists of core members 11 of molded resilient material such as neoprene or polyurethane, covered by a casing material 12. The core members are designed to fit side by side within the cover, and are contoured to shape the finished pad to the space into which it is to be placed. The bottoms 13 of the core members are rounded to form a matching curvature to that of the bottom of the journal box, and the tops 14 are flat. The adjacent surfaces 15 of the core members are also flat.

The cover 12 is composed of two core member-encircling strips 16, one around each core member. The strips

2

are wrapped transversely around the core members, and the edges of the respective strips are joined in horizontal seams 17 along the lower inner edges of the core members. The casing material projects beyond the ends of the core members and a part of the excess is folded inwardly and stitched to provide end hems 18.

End tapes 19 span each end of each core member and have their edges stitched to the end hems 18 of the casings. The end tapes do not cover the entire ends of the core members, but they serve to hold the cores against slipping in the casings.

The two covered core members are joined at their ends either by stitching or by stapling. The lines of joinder 20 may extend all of the way along the projecting vertical adjacent edges of the cover as shown, or the connection 15 may be by a simple stitching of the end edges of the adjacent casing walls top and bottom. This manner of joinder provides a unitary pad, but at the same time, leaves the two covered members free from attachment to one another throughout the greater parts of their lengths.

A pull out strap, or handle, 21 projects beyond one end of the pad to provide means for grasping when the pad is to be withdrawn from a journal box. The strap has ends 22 which extend the full length of the pad, with one 25 end being stitched to the cover of each core member cover.

The casing material used to cover the core members, and which forms the journal-contacting part of the pad, is covered with loops 23 of wicking material. These loops actually contact the journal, and, as they are free to move, 30 they prevent the top surface of the pad from becoming glazed under the constant sliding contact of the journal with the pad.

When the pad of the present invention is inserted into a journal box, it will rest upon the bottom of the box and 35 be partly immersed in oil. The casing, being of very good wicking material, will draw oil to the top of the pad very rapidly. The oil will not only move up the outer sides of the pad and across the top, but will also flow up the center of the pad through the inner walls 24 of the 40 core member casings. Thus, oil, too, will spread out across the top of the pad and the entire top surface will be saturated very quickly, and resupplied as rapidly as it is used up.

Due to the separation of the pad into two units between 45 the ends, there is nothing to impede the free flow of oil along the inner walls 24. This construction assures substantially the same pressure on the core members in all installations, as the units may separate if required to adjust themselves to the journal as needed by the depth from the bottom of the box to the journal. This depth varies considerably depending upon whether the box is a new 50 box, or one that is well worn. Most importantly, the separation of the units between the ends of the pad provides for the ready removal of trash which may get on the operative surface of the pad. The pad seats within the box with the units parallel to the journal axis. This places the line of separation directly under the journal so that any trash which accumulates on the pad can fall freely between the units to the bottom of the box. This 55 makes the pad self cleaning.

The present pad has its bottom contoured to fit the bottom of the journal box, as did the one disclosed in the above mentioned prior patent, and, therefore, it has the same advantages of the prior pad plus the added advantages of unimpeded oil flow, automatic pressure adjustment and self cleaning. Still another advantage of the pad of the present invention is the inability of the bottom ends of the central vertical cover walls 24 shifting to move out of the oil area. These wall ends are fixed in the seams 60 at the bottom edges of the core members.

While in the above one practical embodiment of the

invention has been disclosed, it will be apparent that the details of construction shown and described are merely for purposes of illustration, and the invention may take other forms within the scope of the appended claims.

What is claimed is:

1. A lubricator pad for use in journal boxes comprising, a pair of resilient core members arranged side-by-side, a separate sheet of textile wicking material wrapped and secured around each of the core members providing a separate covering for each core member with a thickness of wicking material over the tops, sides and bottoms of the core members, the sides of the coverings between the side-by-side core members each being a vertical side having top, bottom, front and rear ends, and means connecting the vertical sides of the adjacent coverings between the core members from the bottom to the top of the lubricator pad at the front end and rear end only, whereby when the pad is inserted into a journal box there is nothing to impede the free flow of oil between the adjacent coverings.

2. A lubricator pad for use in journal boxes as claimed in claim 1 wherein, the pad has a transversely rounded bottom and a flat top.
